UNITED STATES PATENT OFFICE.

JAMES H. REED, OF SWAMPSCOTT, MASSACHUSETTS, ASSIGNOR TO UNITED SHOE MANUFACTURING CORPORATION, OF PATERSON, NEW JERSEY, A CORPORATION OF NEW JERSEY.

COP-WINDING MACHINE.

Application filed December 19, 1925. Serial No. 76,480.

The present invention relates to cop winding machines and is herein shown as embodied in a machine for winding from waxed thread a flat disk-like cop for use in 5 a discoidal sewing machine shuttle.

The object of the present invention is to provide a machine by which a flat disk-like cop of waxed thread may be wound easily and conveniently without any particular 10 skill or care on the part of the operator and from which the completed cop may be readily and quickly removed without any liability of injury or distortion.

With this object in view the invention consists in an improved cop winding machine having its various parts constructed and arranged to operate as hereinafter described and claimed.

A machine embodying the present invention comprises two flanges between which the cop is wound and which serve to support the coils of thread at the ends or side faces of the cop and retain the shape of the mass of thread as it is built up, a winding shaft 20 upon which the cop is wound, and a driving shaft for rotating the winding shaft during the cop winding operation. Features of the invention relate to the manner in which the winding shaft is mounted so as to be longitudinally movable into and out of winding position and into and out of engagement with the driving shaft, to the means for readily moving the winding shaft into and out of position and for holding it in winding 30 position, to the simplified construction for holding the end of the thread at the beginning of the winding operation, to the construction and arrangement of the parts permitting the flanges and winding shaft to be 35 properly heated, and to other details of construction and arrangements of parts hereinafter described.

Referring to the accompanying drawings, Fig. 1 is a view in side elevation of a cop winding machine embodying the present invention, the parts being shown in the position which they assume at the beginning of the winding operation; Fig. 2 is a vertical sectional view of the machine with the base portion shown in side elevation; Fig. 3 is a view similar to Fig. 2, but with the parts shown at the completion of the winding operation

and with the winding shaft withdrawn to permit the completed cop to be removed; Fig. 4 is a detail horizontal sectional view 55 of the parts in the position illustrated in Fig. 3; and Fig. 5 is a view in end elevation of the cop which is formed by the machine.

The winding flanges between which the cop is wound are indicated at 6 and 8. Of these flanges the flange 6 is rigidly secured to a driving shaft 10, and the flange 8 is loosely mounted upon a winding shaft 12. The shafts 10 and 12 are mounted in bearings formed in standards 14 and 16 projecting upwardly from a base 18, the two shafts being in axial alignment and the winding shaft 12 being movable longitudinally towards and from the driving shaft but always maintaining its position in axial alignment 70 with the driving shaft. The belt pulley 20 is loosely mounted upon the driving shaft 10 and is connected to the shaft so as to rotate the same at the will of the operator by means of a clutch sleeve 22 splined upon the driving shaft and operated by a bell crank lever 24 connected to a starting and stopping treadle by a link 26.

The winding shaft 12 is rotated only at such times as it is engaged with the shaft 80 10, and in order to cause the winding shaft to be rotated it is provided at its inner end with a projection 28 adapted to be received in a corresponding slot 30 in the end of the driving shaft 10.

The flanges 6 and 8 are provided with opposed parallel faces, and these faces are maintained a fixed distance apart so that they constitute walls between which the coils of thread forming the cop can be received and by which the coils of thread are supported and the entire mass of thread formed and retained in the required shape as it is built up into a cop. To maintain the opposed faces of the flanges at a fixed constant distance from each 95 other the flange 6 is secured to the driving shaft 10, and the flange 8 is provided with a groove 32 which is engaged by a plate 34 secured to or formed on a rod 36 mounted in the bearing post 16 of the frame. A set 100 screw 38 is provided for locking the rod 36 to the post 16, and this construction provides means which permits an adjustment of the flange 8 towards and from the flange 6 for

the production of cops of varying thickness.

In forming a cop, the thread is wound between the flanges 6 and 8 upon the winding shaft 12, and to cause the end of the thread to be gripped by the winding shaft at the start of the winding operation it is provided at its inner end with a thread receiving slot 40. The thread is clamped in the slot between the adjacent ends of the winding and driving shafts, and thus when the cop is completed, as illustrated in Fig. 5, the inner end of the thread is in a position to permit it to be readily withdrawn so that in using the cop the thread can be withdrawn from the center of the cop.

After sufficient thread has been wound upon the winding shaft to form the cop, the thread is severed from the supply, and the winding shaft is withdrawn completely from the interior of the cop which is stripped from the winding shaft as the shaft is withdrawn by the flange 8. The withdrawal movement of the winding shaft is in an axial direction and when completely withdrawn from between the winding flanges the winding shaft still remains snugly fitted in its bearing. The construction for supporting and rotating the winding shaft is thus extremely simple and efficient and permits the operator readily to move the winding shaft into winding position and to remove it from the completed cop without any particular care or skill and without any liability of injuring or distorting the completed cop. This manner of supporting and driving the winding shaft also permits the winding shaft and flanges to be heated readily and in an efficient manner, as will be hereinafter described, so that the cop of waxed thread may be readily removed from the machine without injury.

As a convenient means for moving the winding shaft into and out of winding position, the outer end of the shaft is provided with a block 42 rotatably mounted thereon from which projects pins 44 which are engaged by a slotted fork at the upper end of an arm 46 provided with an operating handle 48. To hold the winding shaft securely in winding position a locking device in the form of a leaf spring 50 is secured to the bearing post 16 and provided with a hole 52 arranged to be engaged by a pin 54 on the arm 46 as the winding shaft reaches its extreme inward position. To limit the outward movement of the winding shaft a guard, or stop, 56 is provided consisting of a plate secured at one end to the bearing post 16 and having its other end bent into a position to extend across the outer end of the winding shaft.

The base 18 of the machine and also a portion of the bearing posts 14 and 16 are made hollow to form a chamber to which steam is supplied through suitably arranged pipes, one of which is shown at 58. The bearing posts are thus heated, and by reason of the

snug fit of the shafts 10 and 12 in the bearing posts heat is conducted in an efficient and satisfactory manner to the shafts and through the shafts to the winding flanges 6 and 8.

The invention having been thus described, what is claimed is:

1. A cop winding machine having, in combination, two winding flanges between which the cop is wound, a driving shaft concentric with the flanges, a winding shaft upon which the cop is wound arranged in axial alignment with the driving shaft, bearings in which said shafts are mounted and in one of which the winding shaft is longitudinally movable from winding position between the flanges to a position permitting discharge of the cop, means for clamping the end of the thread to the winding shaft when in winding position, and cooperating clutch faces on adjacent ends of the shafts to drive the winding shaft from the driving shaft.

2. A cop winding machine having, in combination, two winding flanges between which the cop is wound, a driving shaft concentric with the flanges, a winding shaft upon which the cop is wound arranged in axial alignment with the driving shaft, bearings in which said shafts are mounted and in one of which the winding shaft is longitudinally movable from winding position between the flanges to a position permitting discharge of the cop, means for clamping the end of the thread to the winding shaft when in winding position, and a lever and suitable connections for moving the winding shaft axially from between the winding flanges and for returning it to winding position.

3. A cop winding machine having, in combination, two winding flanges between which the cop is wound, a driving shaft concentric with the flanges, a winding shaft upon which the cop is wound arranged in axial alignment with the driving shaft, bearings in which said shafts are mounted and in one of which the winding shaft is longitudinally movable from winding position between the flanges to a position permitting discharge of the cop, means for clamping the end of the thread to the winding shaft when in winding position, means including a lever and suitable connections for moving the winding shaft axially to winding position, and a device acting on said means to hold the shaft in winding position.

4. A cop winding machine having, in combination, two winding flanges between which the cop is wound, a driving shaft concentric with the flanges, a winding shaft upon which the cop is wound arranged in axial alignment with the driving shaft and longitudinally movable from winding position between the flanges to a position permitting discharge of the cop, means for clamping the end of the thread to the winding shaft when in winding position, and means permitting

adjustment of the flanges toward and from each other to permit cops of different thickness to be wound.

5. A cop winding machine having, in combination, two winding flanges between which the cop is wound, a driving shaft concentric with the flanges, a winding shaft in alignment with the driving shaft movable axially to winding position between the winding flanges and having a thread engaging slot in its end, and means for axially moving the winding shaft.

6. A cop winding machine having, in combination, two winding flanges, a winding shaft concentric with the flanges having a projection on its end, a driving shaft in axial alignment with the winding shaft having a slot to receive the projection on the winding shaft, the winding shaft having a thread engaging slot arranged substantially at right angles to the projection, and means for axially moving the winding shaft.

7. A cop winding machine having, in combination, two winding flanges between which the cop is wound, a driving shaft concentric with the flanges, a winding shaft upon which the cop is wound arranged in axial alignment

with the driving shaft, bearings in which said shafts are mounted and in one of which the winding shaft is longitudinally movable from winding position between the flanges to a position permitting discharge of the cop, means for clamping the end of the thread to the winding shaft when in winding position, and means for heating the bearings and through the bearings the winding shaft and flanges.

8. A cop winding machine having, in combination, two winding flanges between which the cop is wound, a driving shaft concentric with the flanges, a winding shaft upon which the cop is wound arranged in axial alignment with the driving shaft, means for clamping the end of the thread to the winding shaft when in winding position, and a hollow steam heated base having posts provided with bearings in which said shafts are mounted and in one of which the winding shaft is longitudinally movable from winding position between the flanges to a position permitting discharge of the cop.

In testimony whereof I have signed my name to this specification.

JAMES H. REED.
